FRANK W. BUTTERWORTH AND GRANT HOLMES, OF DANVILLE, ILLINOIS, ASSIGNEES
TO WESTERN BRICK COMPANY, OF DANVILLE, ILLINOIS, A LIMITED PARTNERSHIP.

BRICKMAKING-MACHINE.

1.191.925.

Specification of Letters Patent. Patented July 18, 1916.

Application filed March 22, 1916. Serial No. 85,788.

To all whom it may concern:

Be it known that we, FRANK W. BUTTERWORTH and GRANT HOLMES, both citizens of the United States, and residing at Danville, 5 in the county of Vermilion, State of Illinois, have invented certain new and useful Improvements in Brickmaking Machines, of which the following is a specification.

which the following is:

Our invention relates to brick-making machines, and refers particularly to a machine for treating the surface of a ribbon of ceramic material after it has been extruded from the press, according to the well-known stiff-mud process.

15 In the co-pending applications of Frank
W. Butterworth Serial Nos. 46,236, filed
August 19, 1915, and 68,742, filed December
27, 1915, brick-making machines have been
described which have the function of stip-
20 pling the surface of a moving ribbon of clay
or other ceramic material so that this sur-
face is covered with a large number of mi-
nute indentations, which serve to give the
finished bricks very desirable characteristics
25 in that the surfaces of the latter which are
exposed to view have a soft, pleasing ap-
pearance and are light-absorbing rather than
light-reflecting. As described in said ap-
plications, the more or less hardened skin
30 formed on the upper and side surfaces of
the clay-ribbon as it is extruded from the
die of the press is removed therefrom by
wires, or other similar means, preferably
placed near the mouth of said die, this oper-
35 ation also serving to roughen the upper and
side surfaces of the ribbon. The stippling
operation is then performed by means of
brushes carrying steel bristles, which pene-
trate slightly the exposed surface of the rib-
40 bon, thereby giving the latter the desired ap-
pearance. The bristles are preferably made
of hardened steel, and are slightly bent when
brought in contact with the ribbon, so that
upon disengagement therefrom small par-
45 ticles of clay are "picked" from the ribbon.

49 It is the object of our present invention to construct a brick-making machine which shall have the function of stippling the exposed surfaces of the moving clay-ribbon 50 and to perform this operation in an efficient and economical manner, with the expenditure of only a small amount of power for driving the machine.

It is a further object of our invention
55 to provide means by which the stippling

brushes may be readily adjusted with respect to the clay-ribbon so that the bristles of these brushes will penetrate the surface of the ribbon a desired distance.

A still further object of our invention consists in the provision of means by which a plurality of brushes adapted to be brought in contact with one of the surfaces of the clay-ribbon may be maintained in proper alinement, such means being adjustable, so that if desired the brushes as a whole may be regulated in such manner that the bristles of these brushes will progressively sink a greater or less distance into the surface of the ribbon. By the use of such alining means, only a single cam or eccentric need be employed in order to regulate the movement of a series of brushes, thus rendering the machine simple and economical in its operation. 75

These and other advantages of our invention will be more readily understood by reference to the accompanying drawings, in which—

which— Figure 1 is a plan of our improved brick-making machine, showing the complete machine having brushes adapted to engage both the sides and the top of a moving clay-ribbon; Fig. 2 is a plan of that portion of the machine which carries the brushes adapted to engage the upper surface of the clay-ribbon; Fig. 3 is a fragmentary side elevation of the portion of the machine shown in Fig. 2; Fig. 4 is an enlarged end elevation of the portion of the machine shown in Figs. 2 and 3; Fig. 5 is a horizontal section taken on the line 5—5 of Fig. 4; Fig. 6 is a horizontal section taken on the line 6—6 of Fig. 4; Fig. 7 is a side elevation of the portion of the brick-making machine which carries the brushes adapted to engage the sides of the moving clay-ribbon, the conveyer sheaves and their supporting mechanism being omitted for the sake of simplicity; and Fig. 8 is a vertical transverse section taken on the line 8—8 of Fig. 7, showing the conveyer sheaves and their supporting mechanism in position.

The machine of our invention is adapted to treat the ribbon 20, of clay or other ceramic metal, after the latter leaves the brick-press and after the more or less hardened skin has been removed from the upper and side surfaces of this ribbon. The machine as a whole comprises two principal 105 110

- portions, namely, the portion 21 for treating the upper surface of the ribbon 20 and the portion 22 for treating the sides of the ribbon. For the sake of simplicity, I will 5 first describe the detailed construction of the portion 21 of the brick-making machine, then the detailed construction of the portion 22, and finally describe the operation of the machine as a whole.
- 10 The portion 21 of the machine rests on the I-beams 23, being carried thereon by the transverse angle-irons 24, which serve to support the four angle-iron corner posts 25. Near their upper ends the corner posts 25 15 are engaged by the longitudinal angle-irons 26, which are, in turn, engaged by the transverse angle-irons 27 which are riveted or otherwise fastened to the longitudinal angle-irons 26. The longitudinal angle-irons 26 20 and the transverse angle-irons 27 have connected thereto at their points of junction the gussets 28, which have the transversely disposed downward extensions 29, which engage the corner posts 25, the surface 25 of each corner post 25 which is located at a right angle to the surface engaged by the extension 29 of each of the gussets 28 being engaged by a longitudinal angle-iron 26. As most clearly shown in 30 Figs. 4 and 6, each of the four corner posts 25 is engaged on its inner angular surface by the angle-piece 30, which is bolted to one of the longitudinal angle-irons 26 and the extension 29 of one of the gussets 28. Each 35 angle-post is, therefore, near its upper portion inclosed by a longitudinal angle-iron 26 and the extension 29 of the gusset plate 28 on its outer angular portion and the angle-piece 30 on its inner portion.
- 40 The upper end of each corner post 25 has bolted thereto the bearing member 31, through which passes the regulating shaft 32, to the upper end of which is fastened the hand-wheel 33. The shaft 32 carries 45 thereon the collars 34 and 35 engaging opposite ends of the bearing member 31. The lower portion of the regulating shaft 32 is threaded, and engages the correspondingly threaded block 36, the upper end of which 50 in turn engages the lower edge of the angle-piece 30. It will be evident that on rotation of the hand-wheels 33 the regulating blocks 36 are moved upwardly or downwardly, as the case may be, and thereby serve to correspondingly move the framework, which is 55 comprised of the longitudinal angle-irons 26 and the transverse angle-irons 27. Each of the retaining clamps 37, most clearly shown in Fig. 5, incloses the corner post 25 60 and the regulating block 36, and serves to prevent the latter from turning when the regulating shaft 32 is rotated, and also serves to hold the parts in adjusted position upon tightening the hand-screw 38 carried 65 by each of the clamps 37.

At or near their central portions each of the longitudinal angle-irons 26 carries a bearing member 39, and through these bearing members passes the shaft 40 carrying the pulley 41. The shaft 40 at its central portion between the bearings 39 is provided with an eccentric portion 42, which, in turn, engages the bearings 43 carried by the upper surface of the brush-carrying plate 44, so that upon rotation of the shaft 40 the brush-carrying plate is moved toward and away from the ribbon 20 moving through the machine on the endless conveyor 45 carried by the sheaves 46, which are, in turn, carried by the channels 47 resting on the supports 48. The brush-carrying plate 44 has bolted to its lower surface the brushes 49, each of which carries the bristles 50 which are preferably constructed of flat narrow strips of tempered steel.

Bolted to the longitudinal angle-irons 26 are the bearing members 51, one of these bearing members being located near each end of each longitudinal angle-iron 26. Extending between each pair of bearing members 51 is a shaft 52, and rigidly mounted on each of these shafts is a bell-crank lever 53. To one end of each bell-crank lever 53 is pivotally connected a pair of links 54, the opposite ends of which are pivotally connected to one end of the rib 55 of the brush-carrying plate 44.

To the opposite end of each bell-crank lever 53 is pivotally connected the interiorly threaded member 56, and between the two members 56 extends the equalizing rod 57, one end of which, as 58, has a right-handed screw thread and the other end of which, as 59, has a left-handed screw thread. It will be evident that on rotation of the equalizing rod 57 the upper arms of the bell-crank levers 53 are moved toward or away from each other, as the case may be. When the upper arms of the bell-crank levers are thus moved toward each other it will be evident that the horizontal arm of the bell-crank lever, shown at the right-hand portion of Fig. 3, will be moved downwardly, thereby carrying that end of the brush-carrying plate 44 downwardly and moving the brushes 49 at this end of the plate nearer to the ribbon 20. At the same time the horizontal arm of the bell-crank lever 53, shown at the left-hand portion of Fig. 3, will be moved upwardly, thereby carrying that end 120 of the brush-carrying plate 44 and the brushes 49 upwardly. On rotation of the equalizing rod 57 in the opposite direction so that the upper vertical arms of the bell-crank lever 53 are moved away from each other, the opposite action will take place with respect to the movement of the brush-carrying plate 44. In this way it will be evident that the position of the brushes 49 may be regulated as desired, while at the 125

same time upon rotation of the shaft 40 the brush-carrying plate 44 is always maintained at the same angle with respect to the clay-ribbon 20 as the brush-carrying plate 44 and its brushes 49 are moved toward and away from the ribbon 20 by the action of the eccentric 42. As a matter of practice, we usually prefer to maintain the brush-carrying plate 44 in a position exactly parallel to the upper surface of the clay-ribbon 20, but, as previously explained, if it is desired to tilt the plate 44 slightly so that the bristles 50 of the brushes 49 at one end of the plate 44 may penetrate into the upper surface of the clay-ribbon farther than the bristles of the brushes at the opposite end of the plate 44, this result may be readily accomplished.

We will now pass to a description of the portion 22 of the brick-making machine, which is, in many respects, similar to that of the portion 21 just described. As most clearly shown in Figs. 7 and 8, the I-bearings 60 carry the transverse angle-irons 61, to which are suitably fastened the four corner posts 62. To the upper ends of the corner posts 62 are riveted the longitudinal angle-irons 63 and the transverse angle-irons 64, the gussets 65 being used to strengthen the construction. A pair of angle-irons 66 is riveted or bolted to the longitudinal angle-irons 63 near the central portions of the latter. The pair of angle-irons 66 at each end thereof carries an elbow piece 67, each of which is also fastened to one of the longitudinal angle-irons 68 extending between the corner posts 62. Each elbow piece 67 has a bearing 69, through which passes the regulating shaft 70 having at its outer end the hand-wheel 71. The shaft 70 carries thereon the collars 72 engaging opposite ends of the bearing 69. The inner end of the regulating shaft 70 is threaded, and engages the yoke 73, which on its lower surface is provided with the recess 74 for slidably engaging the track 75 of the elbow member 67 and at its upper outer portion has a cross-piece 76 engaging the upper surfaces of the angle-irons 66. The yoke 73 carries thereon the lower bearing member 77 and the upper bearing member 78 located at the inner end of the arm 79 of the yoke member. The bearing member 78 also carries a bracket 80 having flanges which engage the upper surfaces of the angle-irons 66, this bracket, in turn, carrying the bearing member 81.

The shaft 82 extends between the bearing members 77 and 78, and at its central portion is provided with the eccentric 83, which, in turn, engages the bearing 84 carried by the brush-carrying plate 85 near its central portion, this plate, in turn, carrying the brushes 86 having thereon the bristles 87, these brushes 86 and their bristles 87 being of the same character as the brushes 49 and their bristles 50 heretofore described. It

will be evident that upon rotation of the shaft 82 the brush-carrying plate 85 is moved toward and away from the side of the ribbon 20 by the action of the eccentric 83 upon the bearing 84.

The upper end of each shaft 82 carries the beveled gear 88, which is in mesh with the beveled gear 89 carried by the shaft 90. The beveled gear 89 is suitably splined on the shaft 90 so that it is movable longitudinally thereof but rotates with said shaft. The shaft 90 passes through the two bearing members 81, and also through the bearing 91 carried by the bracket 92 supported on the angle-irons 66. At its outer end the shaft 90 carries the pulley 93 suitably driven by a belt or otherwise. By means of the clamp 94, which engages the vertical flanges of the angle-irons 66 and carries the hand-screw 95 which has threaded engagement with the arm 79 of the yoke 73, the latter may be locked in any position to which it is moved by rotation of the hand-wheel 71 carried by the threaded shaft 70. Each of the shafts 96 has engagement at its ends with the bearing members 97 carried by the angle-irons 63 and 68, and has rigidly mounted thereon a bell-crank lever 98. Each bell-crank lever carries pivotally at its outer end the member 99. Extending between the two members 99 located on each side of the portion 22 of the machine is the equalizing rod 100, one end of which is provided with right-handed screw threads and the other end of which is provided with left-handed screw threads. The links 101 are pivotally connected with the opposite ends of the bell-crank levers 98, and extend to and have pivotal connection with the rib 102 of each of the brush-carrying plates 85. It will be evident that on rotation of the equalizing rod 100 the brush-carrying plate 85 and its brushes 86 may be tilted with respect to the ribbon 20 in exactly the same manner as was described in connection with the equivalent parts in the portion 21 of the machine. At the same time the equalizing rods 100 have the function of maintaining the brush-carrying plates 85 and their brushes 86 in proper alignment with respect to the ribbon 20 upon movement of the brush-carrying plates 85 toward and away from the sides of the ribbon 20 by the action of the eccentrics 83.

Having thus described the various parts which are used in our improved brick-making machine, the operation of the same may now be readily understood: As previously explained, the ribbon 20, of clay or other ceramic material, preferably has thin layers of material removed by wires or other suitable means from the upper and side surfaces of the ribbon as the latter leaves the die of the brick-press, according to the well-known method. The ribbon 20 then passes through

the portion 21 of the machine, and its upper surface is subjected to the action of the bristles 50 of the brushes 49. The brush-carrying plate 44 is moved toward and away from the upper surface of the ribbon 20 by the action of the eccentric 42, the shaft 40 being rotated in the direction indicated by the arrow in Fig. 3. In this way the bristles 50 during their period of engagement with the upper surface of the ribbon 20 are moved in the same direction as the movement of the ribbon but preferably at a slightly different rate of speed. During their period of engagement the bristles 50 are slightly bent so that as they approach disengagement from the surface of the ribbon they are straightened and remove small particles of clay from the surface of the ribbon by a "picking" action. As previously explained, the equalizing rod 57 and its associated mechanism keep the brush-carrying plate 44 and the brushes 49 in correct alignment with respect to the surface of the ribbon 20, while at the same time upon rotation of the equalizing rod 57 the brush-carrying plate 44 may be tilted as desired so that the bristles 50 of the brushes carried on one end of the plate may be caused to enter the surface of the ribbon 20 to a greater depth than those of the brushes carried by the other end of the plate 44. The brushes 49 and the mechanism for actuating the same may be readily adjusted by the hand-wheels 33. After leaving the portion 21 of the machine the clay-ribbon 20 passes into the portion 22, where the sides of the clay-ribbon are subjected to the action of the bristles 87 of the brushes 86 in the same manner that the upper surface of the ribbon has been subjected to the action of the bristles 50 of the brushes 49. It will be understood that the function of the equalizing rods 100 is similar to that of the equalizing rod 57, and the position of the brushes as a whole may be regulated by means of the hand-wheels 71.

As a result of the action of our improved brick-making machine, it will be apparent that the upper and side surfaces of the clay-ribbon 20 are roughened and stippled with a large number of minute indentations caused by the bristles 50 and 87. The small particles of clay which remain on the upper surface of the ribbon as a result of the stippling action may be removed therefrom by means of a blower, or other similar means. After the clay-ribbon has passed through our improved machine, it is cut into individual bricks by any well-known process, and these bricks are afterward subjected to the heating action of kilns to produce the finished product.

It will be apparent to those skilled in the art that many detailed changes in the construction of the parts which we have described may be made without departing

from the spirit or scope of our invention, as defined in the appended claims.

What we claim is:

1. In a brick-making machine, the combination of a conveyer adapted to carry a ribbon of ceramic material through said machine, a stippling brush adapted to engage the surface of said ribbon, means for carrying said brush, an eccentric adapted to move said brush-carrying means toward and away from the surface of said ribbon, and means for automatically keeping said brush-carrying means in alignment with respect to said ribbon, said alining means comprising mechanism for selectively changing the angular position of said brush-carrying means with relation to the surface of said ribbon. 75

2. In a brick-making machine, the combination of a conveyer adapted to carry a ribbon of ceramic material through said machine, a stippling brush adapted to engage the surface of said ribbon, a plate carrying said brush, an eccentric adapted to move said plate and brush toward and away from said ribbon, a pair of bell-crank levers having connection with said plate near the ends thereof, and an equalizing rod extending between said levers, whereby said plate is kept in alignment with respect to said ribbon upon actuation of said plate by said eccentric. 85

3. In a brick-making machine, the combination of a conveyer adapted to carry a ribbon of ceramic material through said machine, a stippling brush adapted to engage the surface of said ribbon, a plate carrying said brush, an eccentric adapted to move said plate and brush toward and away from said ribbon, a pair of bell-crank levers having connection with said plate near the ends thereof, and an equalizing rod extending between said levers, said equalizing rod being adjustable to selectively move the connected arms of said bell-crank levers toward or away from each other, whereby the angular alignment of said plate with respect to said ribbon may be adjusted and said plate is automatically maintained in its adjusted alignment upon actuation of said plate by said eccentric. 100

4. In a brick-making machine, the combination of a conveyer adapted to carry a ribbon of ceramic material through said machine, a stippling brush adapted to engage the surface of said ribbon, means for carrying said brush, an eccentric adapted to move said brush-carrying means toward and away from the surface of said ribbon, means for automatically keeping said brush-carrying means in alignment with respect to said ribbon, and means for adjusting the position of said brush-carrying means and its associated eccentric with relation to the surface of said ribbon. 125

5. In a brick-making machine, the combi- 130

nation of a conveyer adapted to carry a ribbon of ceramic material through said machine, a stippling brush having bristles adapted to engage the surface of said ribbon, means for carrying said brush, a yoke, a shaft carried by said yoke, said shaft having an eccentric portion thereon, a bearing on said brush-carrying means and engaged by the eccentric portion of said shaft, means for adjusting the position of said yoke toward and away from said ribbon, means

for rotating said shaft, whereby said brush-carrying means will be actuated toward and away from said ribbon, and means for maintaining said brush-carrying means in 15 alinement with respect to the surface of said ribbon.

In witness whereof, we hereunto subscribe our names this 18th day of March, A. D. 1916.

FRANK W. BUTTERWORTH.
GRANT HOLMES.
